Primary Examiner—Stella Reid**Attorney, Agent, or Firm—Christie, Parker & Hale****[57] CLAIM**

The ornamental design for a display console for ultrasound imaging apparatus, as shown and described.

DESCRIPTION

FIG. 1 is a front elevational view of a display console for ultrasound imaging apparatus, showing our new design;

FIG. 2 is a right side elevational view thereof, the left side elevational view being a mirror image thereof; and, FIG. 3 is a top plan view thereof.

The rear elevational view and the bottom plan view of the design are plain and unornamented.
